UNITED STATES PATENT OFFICE

2,322,026

GAS MIXER

Frederick T. Jaeckel, Wauwatosa, Wis.

Application November 3, 1941, Serial No. 417,654

3 Claims. (Cl. 48—180)

My invention relates generally to improvements in the art of mixing gases and of controlling the flow of gas mixture through conduits, and relates more specifically to improvements in the construction and operation of a unit for automatically mixing fuel gas with air and moisture which may be present in the gas conducting pipe and for insuring uniform delivery of the mixture to a burner or other gas utilizing device.

The primary object of my present invention is to provide a new and useful gas mixer and flow regulator which is simple and compact in construction and which is also highly efficient in operation.

A more specific object of this invention is to provide an improved gas mixing device which may be readily constructed and installed in any gas supply pipe of proper size; and which will thereafter function to automatically and thoroughly mix the gas with air or moisture which may be present so as to produce a homogeneous mixture, and to also produce uniform flow of the mixture to the gas utilizing stove or other apparatus.

Another specific object of the invention is to provide an improved gas mixing unit of durable and compact structure, which may be quickly and safely applied to or removed from a gas feed pipe, and which will separate and collect solid particles being entrained by the gas.

A further specific object of the present invention is to provide an efficient gas mixer which can be manufactured and sold at moderate cost, which may be installed and removed by a novice, and which is especially useful in connection with domestic gas appliances such as cooking stoves and heaters.

These and other objects and advantages of the invention will be apparent from the following detailed description.

A clear conception of the various features constituting my present improvement may be had by referring to the drawing accompanying and forming a part of this specification wherein like reference characters designate the same or similar parts in the various views.

Fig. 1 is a central vertical section through one of my improved gas mixers and a fragment of the pipe to which it is applied;

Fig. 2 is a similar section through a modified type of the improved gas mixer and fragment of the pipe to which it is applied;

Fig. 3 is a transverse section of the assemblage taken along the line 3—3 of Fig. 1;

Fig. 4 is likewise a transverse section of the

assemblage taken along the line 4—4 of Fig. 2; and

Fig. 5 is an end view of the improved gas mixer illustrated in Fig. 1, taken from the convex end thereof.

While the invention has been shown and described herein as being specifically applied to a gas mixer manufactured of plastic, hard rubber or metal and adapted for insertion into a gas stove supply pipe, it is not my desire or intent to thereby unnecessarily restrict the scope or utility of the improvement.

Referring to Figs. 1, 3 and 5 of the drawing, the improved gas mixer therein shown comprises in general, a cylindrical body 10 having a concave end 11 and an opposite convex end 12, a well 13 intermediate the ends 11, 12 and provided with a closure 14, an inlet passage 15 extending from the medial portion of the concave end 11 to the lower side wall of the well 13, and an outlet passage 16 extending from the upper side wall of the well 13 to the medial portion of the convex end 12. The body 10 may be formed of either a plastic, hard rubber, or metallic material and is preferably provided with an integral flange 17, at the concave end 11, and the closure 14 may be formed of cork, rubber, asbestos or the like.

The body 10 is adapted to be positioned within the feed or supply line leading to a gas stove or the like and may be readily inserted at the point where two pipe sections 18, 19 of the feed line are ordinarily united by a union. The union illustrated in the drawing is in common usage and consists of a sleeve 20 having screw thread coaction with the pipe section 18 and being provided with a seating surface 21 at one end and a continuous outwardly directed flange 22 adjacent the surface 21, a sleeve 23 having screw thread coaction with the pipe section 19 and provided at one end with a seat 24 of comparatively soft material surrounded by outer screw threads 25, and a collar 26 provided with a flange 27 adapted to coact with the flange 22 of the sleeve 20 and also being provided with screw threads 28 adapted to coact with the screw threads 25 of the sleeve 23 to draw the seating surface 21 of the sleeve 20 into seating contact with the seat 24 of the sleeve 23 when tightened.

In order to apply my improved gas mixer to a gas feed line, the pipe sections 18, 19 should first be uncoupled by unscrewing the collar 26 from the sleeve 23, and by removing the sleeve 20 from its seated position. The cylindrical body 10 may then be slipped within the pipe section 19 with

the flange 17 in engagement with the end of this pipe section 19 so as to retain the body 10 in position. The pipe sections 18, 19 may thereafter again be united by connecting the screw threads 28 of the collar 26 with the screw threads 25 of the sleeve 23, and firmly uniting the same with the aid of a wrench or the like. When the collar 26 has been tightly screwed upon the sleeve 23, the flange 27 of the collar 26 will co-operate with the flange 22 of the sleeve 20 to force the seating surface 21 into snug contact with the spherical seat 24 of the sleeve 23 thereby producing an extremely tight union and sealing the gas feed line with the improved gas mixer properly positioned therein.

The gas, air and moisture may thereafter be delivered under pressure from a source of supply through the inlet pipe section 18 in relatively unmixed condition before entering the cylindrical body 10 at the concave end 11 via the passage 15. After leaving the passage 15 the gas, air and moisture enter the mixing well 13 wherein they are thoroughly mixed by virtue of the sudden expansion thereof within the well and the constant circulating action therein. As the gas becomes thoroughly mixed with the air and moisture, a homogeneous mixture is produced, and the pressure created by the subsequent gas forces the mixture through the passage 16 and pipe section 19 to the point of combustion. By virtue of the thorough mixing of the ingredients in the well 13 and the reduction in size of the passages 15, 16, the combustible nature of the resulting product is greatly increased, and gas consumption is thereby reduced while a more uniform flame results. The well 13 also serves as a cleaning chamber since any solid particles which might be entrained by the gas, air and moisture through the passage 15, will drop to the bottom of the well 13, thereby assuring delivery of pure mixture through the passage 16, and reducing the possibility of burner clogging. The device may be readily withdrawn from the feed line by uncoupling the pipe sections as heretofore explained, and the plug or closure 14 may be removed to facilitate cleaning of the well 13 when necessary.

In the modification illustrated in Figs. 2 and 4, the closure 14 has been omitted from the well 13, and a band 14' of rubber, asbestos or the like encircling the cylindrical body 10 at the well 13 has been substituted. Since the general construction of the modified device is substantially the same and the union illustrated is identical with that shown in Figs. 1, 3 and 5, the same reference characters have been utilized to designate corresponding parts. The band 14' additionally serves to center the cylindrical body 10 within the pipe section 19, besides functioning as a tight closure for the well 13, and this band is preferably either formed of elastic material or should be slide fitted about the body 10 so as to permit ready access to the well 13.

From the foregoing detailed description, it will be apparent that an improved gas mixer unit is provided, which may be readily constructed of

any suitable inexpensive material such as rubber, metal, plastic or cork, at extremely low cost and may be manufactured in various standard sizes to fit standard gas feed lines. The device may be quickly and properly installed by a novice, and the particular formation of the concave inlet end and convex outlet end and of the passages 15, 16, not only serves to naturally conduct the gaseous constituents to and away from the unit, but also provides an assemblage which facilitates correct installation. While one particular type of standard pipe union has been illustrated, the device may nevertheless be similarly installed where other types of unions are utilized. The improved mixer has proven highly efficient in actual use, and the particular formation of the passages and mixing well insures thorough and complete cleaning and mixing of the elements.

It should be understood that it is not desired to limit this invention to the exact details of construction or to the precise mode of use, herein shown and described, for various modifications within the scope of the claims may occur to persons skilled in the art.

25 I claim:

1. A gas mixer adapted for confinement within a gas pipe, and comprising, a one-piece body having a smooth cylindrical peripheral surface formed for snug axial insertion within the pipe, 30 said body being provided with a medial cylindrical well extending across and approximately perpendicular to the central body axis and open for inspection at said peripheral surface, and said body also having straight cylindrical passages 35 connecting upper and lower portions respectively of said well with the central opposite end portions of the body.
2. A gas mixer adapted for confinement within a gas pipe, and comprising, a one-piece body 40 having a smooth cylindrical peripheral surface formed for snug axial insertion within the pipe, said body being provided with a medial cylindrical well extending across and approximately perpendicular to the central body axis and open for 45 inspection at said peripheral surface, and said body also having straight cylindrical passages connecting upper and lower portions respectively of said well with the central opposite end portions of the body, and a removable closure for the well inspection opening attached to said body.
3. A gas mixer adapted for confinement within a gas pipe, and comprising, a one-piece cylindrical body having a smooth cylindrical peripheral surface formed for snug axial insertion within a 55 pipe and also having a conical recess in one end and a similarly conical projection at its opposite end, said body being provided with a medial cylindrical well extending across and approximately perpendicular to the central body axis and open for inspection at said peripheral surface, and said body also having straight cylindrical 60 passages connecting upper and lower portions respectively of said well with the apices of said conical recess and projection.
